Primary Examiner — Mary Ann Calabrese(74) *Attorney, Agent, or Firm* — Renner Kenner Greive Bobak Taylor & Weber(57) **CLAIM**

The ornamental design for a table, as shown and described.

DESCRIPTION

FIG. 1 is a perspective view of a table showing my new design;

FIG. 2 is a left side elevational view of the table of FIG. 1;

FIG. 3 is a right side elevational view of the table of FIG. 1;

FIG. 4 is a front elevational view of the table of FIG. 1;

FIG. 5 is a rear elevational view of the table of FIG. 1;

FIG. 6 is a top plan view of the table of FIG. 1; and,

FIG. 7 is a bottom plan view of the table of FIG. 1.

The broken lines in the drawings illustrate environment and form no part of the claimed design.
